Patented June 29, 1926.

UNITED STATES PATENT OFFICE.

ALFRED D. MULLER, OF BEVERLY, NEW JERSEY.

INTERCHANGEABLE BOBBIN.

Application filed October 28, 1925. Serial No. 65,370.

This invention relates generally to the textile art and has more specific reference to a bobbin for spinning machines and the like, and the primary object being to provide a bobbin to be employed in conjunction with practically any type of spinning machine and the like.

A further and important object is to provide a bobbin of this character that is equipped with a removable base in order that the interior of the same may be properly machined for securing an even balanced bobbin and wherein through the employing of a multiplicity of base plate construction said bobbin may be readily employed in conjunction with various types of machines.

A further and important object is the provision of a bobbin wherein the external circuit thereof is of such a nature as to prevent any slipping of the yarn or thread thereon.

With the foregoing and other objects in view as the nature of the invention is better understood, the same comprises the novel form, arrangement, and combination of parts hereinafter more fully described and shown in the accompanying drawings.

In the drawings wherein like reference characters indicate like parts in both the views:—

Figure 1 is a view in side elevation, partly in cross section of my improved bobbin, and

Fig. 2 is a base view of the bobbin.

Now having particular reference to the drawing, my novel body comprises a hollow frusto-conical body 5 that is open at its enlarged end and internally threaded as at 6 for receiving an interchangeable disk-like face 7 which may be made to suit any type of spindle in order that the bobbin may be

readily interchangeable for any type of spinning machine, the periphery of the base being obviously threaded for threaded engagement within the body 5.

The exterior surface of the body is 45 knurled as at 8 throughout the major portion of its length for providing a roughened surface which will obviously prevent of the slipping of the thread or yarn being wrapped thereon.

Through the provision of the removable base 7, the interior of the body may be properly machined in order that a true balanced bobbin can be produced which is essential in the efficient operation of the 55 device.

It will thus be seen that I have provided a highly novel, simple and inexpensive form of bobbin that is well adapted for the purposes intended. Even though I have herein shown and described the most preferred embodiment of the invention with which I am at this time familiar, it is nevertheless to be understood that minor changes may be made without departing from the spirit 65 and scope of the appended claims.

Having thus described my invention, what I claim as new and desire to secure by Letters-Patent is:—

1. In a bobbin of the character described, 70 a hollow frusto-conical body open at one end and a base removably associated with the open end of the body.

2. In a bobbin of the character described, 75 a hollow frusto-conical body having a knurled exterior surface and a base removably associated with the body.

In testimony whereof I affix my signature.

ALFRED D. MULLER.
